AIR PISTOL

Wilhelm Foss, Zella-Mehlis, Germany

Application July 22, 1937, Serial No. 155,069
In Germany July 15, 1936

3 Claims. (Cl. 124—15)

The invention relates to air pistols of the type in which the barrel is disposed in front of the air cylinder, which contains a spring-actuated piston for generating compressed air, and the piston is connected with the barrel by a cocking lever and is actuated by swinging the barrel journalled on the air cylinder or frame of the pistol, so that the spring is tensed. In well known air pistols of this type the cocking lever lay partly below the barrel and the air cylinder. This position made the arrangement of the trigger mechanism difficult and gave the grip an unfavorable position and also the weight of the weapon was poorly distributed.

According to the present invention the air pistol is provided with a barrel disposed in front of the air cylinder and oscillatably mounted, and a spring-actuated piston slideable in the air cylinder, and a cocking lever pivoted to the barrel, acting on the piston and disposed above the air cylinder. There is thus space below the air cylinder for the trigger mechanism and the grip, so that the pistol is short and low and with proper distribution of the weight, whereby it is possible to shoot accurately without tiring the hand.

In this arrangement of the cocking lever above the air cylinder which, per se, is well known with air pistols having the barrel above the air cylinder, it is necessary to divert the air flow generated by the piston, which air passes under pressure into the barrel and drives the ball therethrough. The air first forced rearwardly into the air cylinder must vary its direction in order to enter the barrel from behind and be able to discharge forwardly through the bore toward the mouth. The resulting pressure loss reduces the effectiveness of the compressed air generated by the piston. The invention therefore relates to a specific arrangement in connection with the piston and the trigger mechanism by means of which the piston compresses the air in the air cylinder in the direction toward the barrel mouth and forces it in the barrel bore as described in detail hereinafter.

By way of example, two embodiments of the invention are illustrated in the accompanying drawings in which Figures 1 to 3 are side views, partly in section, of the pistol with the air piston and the driving sleeve in different positions; Figs. 4 to 8 are detail views of the pawl and catch rod of the valve body and show them in various positions while engaging and releasing each other; Fig. 9 is a top view of the driving sleeve; Fig. 10 is a rear view of Fig. 9; Fig. 11 is a vertical longitudinal section, partly in elevation, of the

second modification; and Fig. 12 is a rear view of Fig. 11 with the cap omitted.

Referring to the drawings, in all figures 1 designates the barrel of the pistol, which is movably arranged on a pin 4 inserted in the front forked portion 2 of the air cylinder 3. To the rear portion of the barrel above the bore thereof the cocking lever 5 is articulated by means of a pin 6. At its rear end the cocking lever 5 is provided with arms 7 having slots which engage the pin 8 inserted in the driving sleeve 9. The driving sleeve 9 cooperates with the air piston 10 with its packing and the rod 11 with its plate 12. Between the air piston 10 and the hollow cylindrical driving sleeve 9 the piston spring 13 is arranged and supported by an annular shoulder 14 of the driving member. Behind the annular shoulder of the driving member a projection 15 having flattened sides is engaged by the arms 7 of the cocking lever and passed thru by the pin 8. The central portion of the projection 15 has a slot which extends through the shoulder 14 and in which a pawl 16 arranged on the pin 8 is displaceably inserted and guided. For this purpose the pawl 16 possesses an upwardly directed slot 17. The projection 18 of the pawl 16 has a nose 19 over which the plate 12 of the catch rod 11 of the air piston passes. The pawl 16 is subjected to the action of a spring disposed on the pin 20 and having two sides 21 and 22 which, respectively, abut against the driving sleeve 9 and the pawl 16. In this way the pawl 16 tends to swing about the bearing pin 8 in clockwise direction and is held thereon.

The pawl 16 is further fitted with an arm 23 inserted in a slot of the driving sleeve corresponding to its width, and is movable in the slot. The arm 23 has a perforation 24.

Below the air cylinder 3 the trigger mechanism disposed in the grip 25 is arranged and comprises the trigger 27 which can swing about a pin 26 and is flexibly connected with the sear 29 by means of a pin 28 in the trigger 27 and a recess 28a in the sear. The sear 29 slides on a pin 30 in the frame 25 and has a nose 32 passing through a slot 31. When the trigger 27 is pulled, the pin 28 is displaced in the slotted recess 28a until it strikes the right-hand end of the slot and drives and displaces the sear 29 controlled by the spring 33 by causing it to slide on the pin 30 farther to the right until the nose 32 passes under the opening 24 of the arm 23 of the pawl 16. When the pistol is cocked, a pressure is transmitted to the pawl 16 by means of the plate 12 and the nose 19 owing to the adjacent inclined

faces and by the strong piston spring 13, which tends to move the pawl counter-clockwise. This occurs, however, also when the nose 32 of the sear 29 passes under the perforation 24 of the arm 23 which thus enters through the slot 31 the air cylinder 3, whereby the plate 12 of the air piston is released by the nose 19 of the projection 18 of the pawl 16 with the result that the valve body springs forward. The air in front of air piston 10 is forced through the channel 24 into the bore without changing its direction. Then the spring 22 swings back the pawl 16, so that the nose 32 of the sear 29 is released and, after disengagement of the trigger, the sear 29 can re-

10 turn by means of the spring 33 to its initial position to the left which is limited by the pin 30.

15 Fig. 1 clearly shows that the pressure of the very strong piston spring 13 cannot act directly on the trigger which would otherwise be difficult to work. The pressure is rather divided into two components at the nose 19, and the larger component acts in horizontal direction and the smaller one in vertical direction. The latter component tends to turn the pawl 16 anticlockwise and thus causes the pawl to exert some pressure upon, or offer resistance to, the nose 32 of the sear 29 with its arm 23, but this resistance is diminished in proportion to the leverage, so that the type of trigger mechanism provided by

20 30 the invention insures small trigger resistance and thus safe shooting.

During cocking the driving sleeve 9 of the valve is drawn forward by the bending of the barrel and the tensioning of the piston spring 13 from the position shown in Fig. 1 until the nose 19 reaches the plate 12. During farther advance of the driving sleeve 9 the pawl 16 is pressed back against the pressure of the spring member 22 so as to slide over the pin 8. Simultaneously, a swinging motion occurs until the plate 12 can slide over the nose 19, as indicated in Fig. 5. At still farther advance of the driving sleeve 9 the plate 12 is caught by the pawl 16 while the latter is returning to its original position, as indicated in Figs. 2 and 6. When the barrel tilts back, the air piston in the air cylinder is taken back by the driving sleeve. In the end position the arm 23 is above the slot 31 in the air cylinder 3 and the front end thereof is supported by the nose 32 of the sear 29, as shown in Fig. 7. When the trigger 27 is now drawn back, the nose 32 will pass under the opening 24 in the arm 23, so that the pawl 16 can yield to the pressure of the plate 12 and swing, whereby the nose 32 is caused to enter the opening 24 and the plate 12 of the air piston is released to permit the spring 13 to throw the air piston forward. The air in front of the air piston 10 is forced through the channel 24 into the bore without altering its direction.

50 In the construction shown in Figs. 11 and 12 the pawl 16 is not displaceably but only turnably arranged on the pin 8 and is subjected to the pressure of the spring 40 which is disposed in the driving sleeve. During the cocking operation the pawl 16 is rotatably moved while the air piston 12 of the valve slips over the nose 19 of the pawl. Owing to spring pressure, the nose 19 comes up again after the plate 12 and holds the air piston. When the barrel is tilted back, the 55 pawl 16 by means of the driving sleeve 9 pushes therefore the air piston into the position shown in Fig. 11. The air piston is released by the return motion of the trigger 27 into the dash and dot position during which motion the trigger is 70 75 swung about the pin 26. The link 41 between

the trigger 27 and the sear 29 is articulated to the pins 28 and 42, and the sear 29 is rotatably disposed on the stationary pin 43. When the trigger 27 is moved about the pin 26, the intermediate joint 41 turns the sear 29 about the pin 43. After a short motion the rounded head 44 of the sear 29 strikes the face 45 of the pawl 16. The trigger has then to overcome the additional pressure of the spring 40, and this transition is felt as pressure point. At further motion of the trigger the head 44 of the sear 29 begins to turn the pawl 16 about the pin 8 until the nose 19 releases the plate 12, the sear 29 passing during this operation through a slot 46 in the cylinder 3.

To provide for a lighter or more difficult release of the shot the driving sleeve 9 contains a regulating screw 48 which is accessible from without through a perforation 47 in the cocking lever 5 and in the cylinder. The more the screw 48 is screwed in, the smaller is the extent to which the nose 19 can engage behind the catch plate 12 and the sooner will the air piston be released during actuation of the trigger. When released, the air piston moves into the position designated by dots and dashes.

During the cocking operation the barrel is tilted, so that the cocking lever 5 by means of its arms 7 draws the driving sleeve 9 to the front until the plate 12 snaps into position behind the nose 19 of the pawl 16.

I claim:

1. An air pistol comprising a grip portion, a cylinder above said grip portion, a barrel pivoted at the front end of said cylinder, air compressing means in said cylinder, said means including a piston, catch means on said piston, a member to the rear of said piston, a spring engaged between said member and piston and compressible therebetween, a detent on said member engageable with said catch means, said piston and member being slidable in said cylinder, connecting means attached to said barrel and said member for sliding said member forwardly to compress said spring and to engage said detent with said catch means when said barrel is pivoted downwardly and for sliding said member and piston rearwardly in said cylinder when said barrel is pivoted back to a firing position, and trigger means for releasing said piston from said detent.

2. An air pistol as claimed in claim 1, said connecting means comprising a lever attached to said barrel behind the pivot point thereof, said lever extending from said barrel to said member above said cylinder.

3. An air pistol as claimed in claim 1, said catch means comprising a rod extending rearwardly from said piston, a plate at the rear end of said rod, the front of said plate having an inclined surface, a pivot mounted across said member, a portion of said detent having a downward and rearwardly extending slot therein, said pivot being engaged by said slotted portion, a second spring attached to said member and engageable with the rear end of said detent, and a nose on said detent in front of said portion, said nose being engageable with said inclined surface, said cylinder being adapted and arranged to allow a limited vertical movement against the action of said second spring of the rear portion of said detent when said member is in the forward portion of said cylinder, and to allow vertical movement controlled by said trigger means when said member is at the rear of said piston.
